CLAIM

The ornamental design for a front panel for a portable time code generator, as shown and described.

DESCRIPTION

FIG. 1 is a front elevational view of a front panel for a portable time code generator according to my new design;

FIG. 2 is a side elevational view thereof, the other side being a mirror image;

FIG. 3 is a back elevational view thereof;

FIG. 4 is a top plan view thereof, the bottom plan view being substantially identical; and,

FIG. 5 is an enlarged side view thereof of a portion of the front panel taken along lines 5:5 of FIG. 1.

FIG. 1

FIG. 2

FIG. 3

FIG. 4

FIG. 5
